UNITED STATES PATENT OFFICE.

SIGMUND BERGMANN, OF NEW YORK, N. Y., ASSIGNOR TO THE AMERICAN BELL TELEPHONE COMPANY, OF MASSACHUSETTS.

TELEPHONE-SUPPORT.

SPECIFICATION forming part of Letters Patent No. 392,843, dated November 13, 1883.

Application filed September 25, 1885. Serial No. 178,166. (No model.)

To all whom it may concern:

Be it known that I, SIGMUND BERGMANN, of New York city, in the county and State of New York, have invented a certain new and 5 useful Improvement in Telephone-Supports, of which the following is a specification.

My invention relates more especially to that class of telephones having a body of oil or equivalent mobile material for controlling the 10 action of the electrodes, such as described in my application No. 113,502.

The object I have in view is to produce such a construction of this and similar instruments and the support for the same that the telephone 15 may be adjusted to the height of the user, but will always retain a level horizontal position, so as not to affect the adjustment. This I accomplish by hanging the telephone on horizontal pivots, well above the center of gravity, 20 on an arm pivoted at its inner end, the telephone-case being weighted at the bottom, or a weight being attached thereto, or being otherwise arranged in any well-known way to throw the center of gravity below the axis of the 25 telephone and insure the maintaining of the telephone in a horizontal position, notwithstanding the turning of the arm on which it is mounted.

In the accompanying drawings, forming a 30 part hereof, Figure 1 is a side view of telephone and arm; Fig. 2, a top view of same, and Fig. 3 a sectional view of the telephone.

The telephone A has one electrode mounted in a body, *a*, of oil or equivalent mobile ma-

terial, and to maintain the adjustment it is necessary that the instrument should be kept in a horizontal position. At the same time it is desirable that the instrument should be capable of vertical adjustment to bring it to the proper elevation for different users. To accomplish this I use a turning-arm, B, pivoted at its inner end, at *b*, to a suitable support, and having a friction-washer, *c*, or other suitable device for holding the arm at any point of adjustment. 35

The outer end of the arm is forked, the ends of the forks *d e* carrying between them on pivots *f g* the telephone A. These pivots are pointed screws setting into countersinks in lugs on the case of the telephone above the center 40 of gravity and forming a loose joint, permitting the free swinging of the telephone to retain its horizontal position. 45

The telephone-case may have a heavy bottom, *h*, to insure stability. 50

What I claim is—

The combination, with a telephone containing a body of mobile material, of a vertically swinging arm upon which said telephone is pivoted above the center of gravity, substantially as and for the purpose set forth. 55

This specification signed and witnessed this 22d day of September, 1885.

SIGMUND BERGMANN.
